(57) **CLAIM**

The ornamental design for a display panel with graphical user interface as shown and described.

DESCRIPTION

FIG. 1 is a first image thereof, according to an embodiment; FIG. 2 is a second image thereof, according to an embodiment;

FIG. 3 is a third image thereof, according to an embodiment; FIG. 4 is a fourth image thereof, according to an embodiment;

FIG. 5 is a fifth image thereof, according to an embodiment; and,

FIG. 6 is sixth image thereof, according to an embodiment. The appearance of the transitional image sequentially transitions between the images shown in FIGS. 1-6. No ornamental aspects are associated with the process or period in which one image transitions to another image. The outermost broken line rectangle shows a display panel, and forms no part of the claimed design.
